UNITED STATES PATENT OFFICE.

GEORGE C. LYNCH, OF NEW YORK, N. Y.

CIGAR-HOLDER AND ASH-RECEPTACLE.

1,015,697.

Specification of Letters Patent. Patented Jan. 23, 1912.

Application filed January 6, 1911. Serial No. 601,217.

To all whom it may concern:

Be it known that I, GEORGE C. LYNCH, of the city of New York and State of New York, have invented certain new and useful 5 Improvements in Cigar-Holders and Ash-Receptacles; and I do hereby declare the following to be a full, clear, and exact description of the invention, such as will enable others skilled in the art to which it 10 appertains to make and use the same.

My invention contemplates an improved cigar holder and ash receptacle preferably made of brass and of ornamental design and adapted to constitute an article of furniture for use in houses, clubs, etc.

In the accompanying drawing Figure 1 is a vertical sectional view of an article constructed in accordance with my invention. Fig. 2 is a top plan view.

Referring to the drawing 1 designates a base or pedestal which is hollow at its central portion and equipped with a hinged door 2 opening downward as indicated in dotted lines. Surrounding its central hollow portion the base is weighted as by steel 25 rings 3 to insure a firm support.

4 designates the tubular column or post extending upward from the base and in alignment with the hollow portion of the latter, and supporting at its top the cigar holder 5, the latter having a central aperture registering with the tubular post. I have shown the holder 5 provided with a wire frame 6 tending to prevent the accidental dropping of cigars into the holder and also allowing means for removing ashes 35 from burning cigars. I have also shown the holder equipped with a transverse bridge 7 having cigar receptacles 8 formed

40 therein and constituting a support for a match receptacle, which latter is preferably constructed in accordance with Letters Patent No. 947,666, issued to me January 25th, 1910.

45 In use the article, preferably of ornamental brass and of approximately the height of the average desk or table, may be moved

to any desired place as customary with articles of this nature, but upon dropping ashes, matches or burned cigars into the 50 holder 5, the latter, instead of retaining them, simply acts as a hopper to conduct them into the tubular post 4 through which they fall to the receptacle in the base or pedestal, and from which they may be removed subsequently through the door 2.

It is obvious that the article may be used for some time without necessitating emptying and that under normal condition the ashes and burned cigars within the receptacle 60 will be so far removed from the cigar holder that their odor cannot occasion annoyance. The construction of the base is such that it will withstand considerable jar without falling over. Even if it should fall the ashes 65 would not be spilled upon the floor or carpet.

I claim as my invention:—

1. As an article of manufacture, a combined cigar holder and ash receptacle, comprising a hollow closed base or pedestal 70 adapted to rest upon a floor and having a door in its under side, a hollow post extending upward from said base to a point within reach of a user, and a cigar holder supported by said post and having an aperture 75 through which ashes, etc., may pass to said post and pedestal.

2. As an article of manufacture, a combined cigar holder and ash receptacle, comprising a hollow closed base or pedestal 80 weighted at its edge and equipped with a door in its under side, a hollow post extending from said base, a cigar holder supported by said post and having an aperture 85 in line with said post, and a match receptacle on said holder.

In testimony whereof, I have signed this specification in the presence of two subscribing witnesses.

GEORGE C. LYNCH.
